SAXOPHONE

Fred N. Meyers, Cleveland, Ohio, assignor to The
H. N. White Company, Cleveland, Ohio, a cor-
poration of Ohio

Application November 24, 1950, Serial No. 197,216

4 Claims. (Cl. 84—385)

1

This invention relates to wood-wind musical instruments and more particularly to improvements and structural refinements of the tampion actuating mechanism of a saxophone operated by the little finger of the left hand.

Heretofore, saxophones due to their inherent structural limitations and variations presented many objectionable features from the standpoint of the musician. For example, the mechanism serving to transfer motion from the keys operated by the little finger of the left hand to the tampions controlling the tone holes in the lower register embodied an excessive number of moving parts having considerable lost motion therebetween resulting in undesirable noise due to such lost motion and a sluggishness in the reaction of the tampions to the movement of the operating keys. Furthermore, prior saxophones were open to the objection that there was considerable variation in the amount of force and pressure angles required by the little finger thereby mitigating against smooth manipulation of the operating keys of the instrument.

It is among the objects of the present invention to provide a saxophone which overcomes the foregoing undesirable features and drawbacks of prior instruments and which readily lends itself to smooth and evenly balanced operation which is capable of rapid manipulation.

Another object of the present invention is to provide a saxophone wherein the tampions controlling the tone-holes in the lower register are located on one side of the bell with the finger actuating keys therefor positioned on the remote side and the operating mechanism therebetween consisting of a minimum number of moving parts.

A further object of the present invention is to provide in a saxophone, tampion operating mechanism positioned between keys actuated by the little finger of the left hand and tampions positioned on the opposite side of the bell, which translates motion therebetween with a minimum change in direction.

A still further object of the invention is to provide in a saxophone construction a key arrangement wherein greater leverage may be obtained resulting in greater ease and speed of operation of the instrument.

Another object of the invention is to provide in a saxophone structure tampion operating mechanism embodying fewer moving parts confined to a minimum of space and whereby motion is translated between the actuating keys and the tampions covering the tone-holes of the lower register of the instrument in such a manner as to

2

obtain uniform response to movement of all the keys.

These and other objects and advantageous features of the invention not at this time more particularly pointed out will become more apparent as the nature of the invention is better understood from the following detailed description taken in conjunction with the accompanying drawings, wherein like reference characters de-

10 note corresponding parts and wherein:

Figure 1 is a fragmentary side elevational view of a saxophone embodying the improvements of the present invention, numerous details of the instrument not required to illustrate the present invention being omitted.

Figure 2 is a fragmentary front elevational view illustrating the body of the saxophone rotated into position to best show the tampion operating mechanism for the tone-holes in the lower register to which this invention is applicable,

Figure 3 is a developed view of the structure shown in Figure 2,

Figures 4 to 8 inclusive are sectional views taken on the lines 4—4, 5—5, 6—6, 7—7 and 8—8, respectively, of Figure 3, illustrating the mechanism with relation to the body and bell portion of the saxophone.

In the drawings many of the parts of the saxophone have been omitted in order to more clearly illustrate the novel features of the present invention. It is, therefore, to be understood that the following description is to be considered as relating to a saxophone having all the necessary parts including such parts and mechanism as are well known in the art and the novel parts in 30 the mechanism disclosed herein whereby an instrument of the improved construction herein contemplated is provided.

With reference to the accompanying drawings, there is illustrated a saxophone constructed in accordance with the teachings of the present invention and embodying a bell 10, a U-shaped tubular member or bow 11 and a tubular body 12. The bell 10 is provided, in the usual manner, with tone-holes 13 and 14 for producing the B_b and B natural notes, respectively, and tone-hole 15 is provided in the bow 11 for producing the C[#] note. The tone-holes 13, 14 and 15 are controlled by valve members or tampions 16, 17 and 18, respectively. The actuating mechanism for the tampions 16, 17 and 18 is mounted on the front of the tubular body 12, as best illustrated in Figures 2 and 3, and includes a plurality of longitudinally extending rods arranged to occupy the 40 50 55 minimum of lateral space, one end of each of

the rods being connected to one of the tampions and the other end to the actuating key therefor.

For actuating the B_b tampion 16 there is provided rod 19 which is rotatably mounted on pivot points projecting in opposed relation from spaced posts 20 and 21 secured to the tubular body 12 as will be more particularly described herein-after. An arm 22 carrying the B_b tampion on its outer end is integrally connected to rod 19 for movement therewith. The tampion 16 is normally maintained in spaced relation or open with respect to tone-hole 13 by means of needle spring 23 secured to the post 20 and engaging a lug 24 mounted on the rod 19. The rod 19 is actuated by the B_b key 25 mounted on the end of arm 26, the other end of which is secured to the rod 19. When the B_b operating key is depressed this movement is translated direct to the rod 19 which is rotated in a counter-clockwise direction as viewed in Figure 6, moving the tampion 16 to close the tone-hole 13.

The B natural tampion 17 mounted on the end of arm 27, is actuated by rod 28. The rod 28 consists of a plurality of sections 29, 30 and 31 integrally connected together with the central section 29 laterally offset with respect to the end sections 30 and 31 which are tubular. The rod 28 is supported at one end by an elongated pin 32a which projects through an opening in post 32 and is threaded into post 21 with the pointed end projecting into one end of the rod 18 and providing a pivotal support therefor. Similarly the other end 31 of the rod 28 is supported by means of the elongated pin 31a projecting through an aperture in the post 33, through the hollow rod section 31 and threaded into the post 20 with the end thereof projecting beyond the post and into the other end of rod 19, providing a pivotal support therefor. The rod sections 30 and 31 are disposed in alignment with the rod 19.

The arm 27 carrying on its outer end the tampion 17 associated with the B natural tone-hole is secured to the rod section 31 and the B natural operating key 34 is mounted on the outer end of arm 35 which is secured to the rod section 30. Rotation of the rod 28 controlling the tampion 17 through key 34 is resisted by needle spring 36, one end of which is secured to the post 33 and the other end engages lug 37 mounted on the rod section 31. The B natural key 34 is provided with a projection 38 extending into the path of movement of the B_b key 25 in such a manner that depressing the B_b key 25 carries with it the B natural key 34 effecting simultaneous operation of both tampions 16 and 17.

The C[#] tampion 18 is mounted on the end of arm 40 which is secured for movement with the actuating rod 41. The rod 41, one end of which is supported on pivot screw 42a threaded into post 42, extends through notches formed in the posts 33, 20 and 21 and has its opposite end supported by pivot screw 32a threaded into post 32. The rod 41 is arranged to be diametrically positioned between the rod 19 and the outer surface of the body 12. The tampion 18 is normally maintained in a closed position by means of the needle spring 43 secured to the post 42 and engaging a lug 44 on the rod 41. The latter is rotated to open the tone-hole 15 as distinguished from the B natural and B_b tampions which are normally closed by rotation of their actuating rods 28 and 19, respectively.

Thus the C[#] tampion is closed when the B natural and B_b tampions are opened and vice versa, upon rotation of their respective operating

rods. For this purpose there is provided spaced posts 46 and 47 laterally offset from the posts 32 and 21 for supporting therebetween a countershaft 45. The countershaft 45 has rotatably mounted thereon a sleeve 45a to which is secured one end of arm 49, the other end having mounted thereon the C[#] key 48. Rotative movement of the sleeve 45a is translated to the rod 41 to effect rotation in the opposite direction through the medium of rocker arm 50 mounted on the sleeve 45a which is adapted to engage a rocker arm 51 secured to the rod 41. Thus depressing the C[#] key 48 rotates the sleeve 45a which in turn through the rocker arms 50 and 51 permits rotation of the rod 41 in an opposite direction in response to the needle spring 43 opening the tampion 18. Rocker arms 50 and 51 are maintained in contact by needle spring 52 anchored to the post 46 with its free end engaging the rocker arm 50.

With reference to Figures 2 and 3 there is particularly illustrated the arrangement of the operating mechanism for the tampion controlling the G[#] tone-hole which similarly to the B_b, B natural and C[#] tampions hereinbefore described, is actuated by the little finger of the left hand. The numeral 60 designates the G[#] tone-hole having tampion 61 associated therewith. The tampion 61 is carried on the end of arm 62 which is anchored for movement to rod 64 pivotally supported by spaced posts 65 and 66. Similarly to tampion 18, tampion 61 is maintained seated on tone-hole 60 by means of needle spring 67 secured to post 66 with its free end engaging lug 68 carried on rod 64. Oscillation of rod 64 is effected to open the tone-hole 60 by depressing the G[#] actuating key 69 which is carried on the end of arm 79 attached to a sleeve 71 rotatably mounted on the countershaft 45. A rocker arm 72 carried by sleeve 71 engages and actuates a rocker arm 73 secured to the rod 64. The G[#] key 69 is operatively connected to the C[#] key 48 through an outwardly extending lug 74 carried on the lower surface of the key 69 and projecting into the path of the C[#] key 48. The G[#] key is also operatively connected to the B natural key by means of arm 75 mounted on the lower surface of key 34 and extending to a position below the key 69.

With reference to the cluster of operating keys it is to be noted that when the G[#] key 69 is depressed to open the tone-hole 60 all other keys remain in their normal inoperative position. When the C[#] key 48 is moved it carries with it G[#] key 69. Thus both tone-holes 60 and 15 are uncovered upon the actuation of key 48. When the B natural key 34 is depressed it also carries with it G[#] key 69. Thus when tone-hole 14 is closed tone-hole 60 is opened. When B_b key 25 is depressed it carries with it B natural key 34 and G[#] key 69 thus closing tone-holes 13 and 14 and opening tone-hole 60. In case C[#] key 48 and B natural key 34 are unintentionally depressed together, to prevent a false note, pick-up levers 80 and 81 (see Figures 3 and 8) carried on rods 31 and 41, respectively, are brought into engagement thereby reclosing C[#] tampion 18 and maintaining same closed to give a true B natural note.

Having thus described my invention so that those persons skilled in the art may understand and practice the same, what I desire to obtain by Letters Patent is embodied in the appended claims.

I claim:

1. A musical instrument of the wood-wind type comprising a tubular body and a bell spaced therefrom, a plurality of vertically spaced apart tone-holes positioned in one side of said bell, tampions for controlling said tone-holes, actuating keys mounted on the side of said tubular body opposite to the side thereof corresponding to the side of the bell upon which said tone-holes are located, a plurality of longitudinally extending rods serving to translate motion from said keys to said tampions, said rods being supported in spaced relation on said tubular body between said tubular body and said bell in a plane parallel to a plane through the axes of said body and bell.

2. A musical instrument of the wood-wind type comprising a tubular body and a bell spaced therefrom, a plurality of vertically aligned tone-holes positioned in one side of said bell, tampions for controlling said tone-holes, actuating keys mounted on the side of said tubular body opposite to the side thereof corresponding to the side of the bell upon which said tone-holes are located, a plurality of oscillating rods serving to translate motion from said keys to said tampions, said rods being arranged one above the other in a plane through the longitudinal axes of said body and bell and supported upon said tubular body between said tubular body and said bell, and means adjacent the keys for effecting reversal of the oscillating movement of one of said rods with respect to the other.

3. A saxophone comprising a tubular body and a bell laterally spaced therefrom, B_b and C[#] tone-holes positioned in spaced relation in one side of said bell, tampions for controlling said tone-holes, means for normally maintaining the tampon for the B_b tone-hole open and the tampon for the C[#] tone-hole closed, keys for actuating said tampions mounted on the side of said tubular body opposite to the side thereof corresponding to the side of the bell upon which said tone-holes are located, a rod mounted on the tubular body serving to translate direct motion from one of said keys to the B_b tampon, a second rod positioned between said first rod and the tubular body for releasing the means for holding the tampon closing the C[#] tone-hole, said rods being positioned between said tubular body and said bell in a plane parallel to a plane through the axes of the tubular body and bell and means

adjacent the said keys for effecting a reverse movement of the second rod with respect to the first rod.

4. A saxophone comprising a tubular body and a bell laterally spaced therefrom, B_b, B natural and C[#] tone-holes positioned in spaced relation in one side of said bell, tampions for controlling said tone-holes, means for normally maintaining the tampions for the B_b and B natural tone-holes open and the tampon for the C[#] tone-hole closed, keys for actuating said tampions mounted on the side of said tubular body opposite to the side thereof corresponding to the side of the bell upon which said tone-holes are located, a rod mounted on the tubular body serving to translate direct motion from one of the B_b keys to the B_b tampon, a second rod having end portions in alignment with said first rod, said end portions being connected to the B natural key and tampon, respectively, for controlling the B natural tone-hole, and a third rod positioned between said first rod and the tubular body for releasing the spring pressure means holding the tampon closing the C[#] tone-hole, and means adjacent the said keys for effecting a reverse movement of the third rod with respect to the first two rods, said rods being positioned between said tubular body and said bell in a plane parallel to a plane through the axes of the tubular body and bell.
